INVENTOR

E. A. TURNER

UNITED STATES PATENT OFFICE

EDWIN ARCHER TURNER, OF NEW YORK, N. Y., ASSIGNOR TO THE STANDARD STOKER COMPANY, INCORPORATED, A CORPORATION OF DELAWARE

LOCOMOTIVE BOILER

Application filed May 26, 1930. Serial No. 455,543.

My invention relates to railway rolling stock and especially to improvements in the construction of the locomotive boiler backhead.

5 The general object of the invention is the provision of a novel and improved locomotive boiler backhead construction wherein the design is materially simplified, and a more durable structure is provided, in which the 10 weight is reduced, and the cost of construction and maintenance lowered.

More particularly, it is an object of this invention to provide in a locomotive boiler, a construction in which the front and rear 15 sheets of the boiler backhead are formed as an integral casting.

A further object of the invention consists in forming the boiler backhead and stoker conduit as an integral casting.

20 A still further object of the invention is the provision of a boiler backhead having deck supports and grate shaker crank brackets cast integrally therewith.

These and other objects and advantages 25 which consist in the novelty of construction will be apparent and fully described in the following description when read in connection with the accompanying drawings, in which

30 Fig. 1 is a central longitudinal section through the novel backhead construction with parts of the locomotive structure shown conventionally;

Fig. 2 is an end elevation of the invention 35 when viewed from without the firebox; and

Fig. 3 is an end elevation of the invention, with parts broken away, when viewed from within the boiler firebox.

Heretofore it has been the practice in the 40 railway industry to form the boiler backhead of two sheets, commonly referred to as the firedoor sheet, to which the inside sheets of the boiler are fastened, and the back sheet to which the outside sheets of the boiler and 45 various locomotive accessories are secured.

Due to the stresses developed within the boiler by the intense heat and generation of steam, the inner and outer sheets of the boiler tend to distort and pull away from one another. This condition is more pronounced 50 at the backhead due to the higher range of temperatures within the firebox in this region.

To overcome this serious condition, the inside and outside sheets of the boiler were tied together by means of stay bolts passed 55 through each and fastened securely in a manner which is well known. The use of stay bolts has been found to be objectionable due to high maintenance cost occasioned by frequent inspection and replacement of these 60 boiler staybolts. This not only meant the expenditure of much time and money, but also caused the locomotive to be placed out of service to permit making these repairs.

While the staybolts at the side sheets of 65 the boiler are readily accessible for inspection and replacement, much difficulty is experienced in inspecting and renewing staybolts in the back sheet of the boiler. This is due to the mounting of numerous locomotive accessories on the back sheet; also, a part of the back sheet is generally located beneath the cab deck and this necessitated the removal of the cab deck in order that access to the staybolts might be gained.

70 With the modern tendency of railroads to use higher boiler pressures on locomotives to increase their capacities and economies, the extended use of staybolts has greatly increased the maintenance of the locomotive.

75 My present invention obviates the use of staybolts in the backhead with a degree of safety never before attained and the invention contemplates designing the locomotive backhead wherein the stoker conduit deck support and grate shaker crank supports are incorporated as an integral part of the backhead structure.

80 While the main object of the invention is the provision of a backhead having its inner 85

and outer sheets formed as an integral casting, of almost equal importance is the provision of a stoker conduit, grate shaker supports and deck supports as an integral part 5 of the backhead structure. Other locomotive accessories may be incorporated as an integral part of the backhead and also any or all of the accessories shown may be omitted without departing from the scope of this invention.

Referring to the drawings and particularly to Figure 1, a locomotive 10 is provided with a boiler 11 having a firebox 12 and a steam generating chamber 13. The rear-most portion of the boiler 11 is enclosed by a novel backhead structure 14 having the usual firing opening 15 formed therein. The backwall 16 and the firedoor sheet 17 of the backhead 14 are formed as an integral casting, and are provided with lateral extensions 18 and 19 to which are secured in any suitable manner the roof sheet 20 and crown sheet 21 respectively.

The lower portion of the backhead 14 is 25 secured to a foundation ring 22 which is provided with a downwardly extending flange 23. A plate member 24 carried by the locomotive 10 is secured to this downwardly extending flange 23 to provide a support for 30 the boiler 11 in a well known manner.

The cross wall 25 between the backwall 16 and the firedoor sheet 17, forms an arcuate roof portion of the firing opening 15. A continuation 26 of the cross wall 25 bounds the 35 remaining portion of the firing opening 15. Extending radially from the cross wall 25 of the firing opening 15 and its continuation 26 are web portions 27 which form a firm union between the backwall 16 and the firedoor sheet 17. Web portions 27 are perforated as 40 at 28 to reduce weight, provide free circulation of water and readily vent to the chamber 13 any steam which may be formed in the lower portion of the backhead 14.

In communication with the lower portion 45 of the firing opening 15 is an aperture 29 serving as a discharge opening for a stoker conduit 30 which is preferably formed as an integral part of the backhead structure 14. The stoker conduit 30 extends rearwardly and 50 downwardly of the backhead 14 and terminates at its rearward portion beneath the locomotive cab deck 31 in a spherical seat 32 adapted to form a ball and socket connection 55 with a fuel transferring means from the locomotive tender, not shown. The stoker conduit 30 is substantially supported from the backwall 16 by a web portion 33 formed integral therewith.

Preferably, though not necessarily, the 60 stoker conduit 30 is circular in cross section and is shown as flaring outwardly at its discharge opening 29. Directly beneath the floor portion 34 of the stoker conduit 30 and adjacent the backwall 16 is a rectangular opening

35 arranged to receive any suitable steam jet. Forwardly of the backwall 16 and at the lower margin of the firing opening 15 is an upright wall 36 to which a fuel distributing member may be secured through the threaded holes 37 in said wall.

Beneath the firing opening 15 and extending laterally from the backwall 16 are the flange portions 38, which are cast as a part of the backhead structure 14, and are utilized to support the locomotive cab deck 31. Projections 39 which serve as grate shaker crank supports are also cast integrally with the backhead structure and are preferably located near the lower margin of the backwall 16.

The specific illustrations shown in the drawings and corresponding specific description herein are used for the purpose of disclosure only, but it will be realized that the substance and essence of the invention may be embodied in other forms as well as those shown.

I claim:

1. A locomotive boiler backhead constituted by an integral casting consisting of an outside wall and a shorter inside wall, the two walls being spaced apart and connected by an imperforate angularly disposed wall portion forming the boundary of a firing opening through the backhead, the end portions of the outside and inside walls being flanged or forwardly turned, an integral central vertical rib perforated at intervals extending between the outside and inside walls and also connecting their forwardly turned flanges, similar perforated ribs angularly disposed to the central rib and spaced therefrom extending diagonally outward from the firing opening, and the lower marginal edges of the outside and inside walls being spaced to provide an opening for the insertion of a foundation ring, all of said perforated ribs at their outer portions extending to the marginal edge of the forwardly extending flange of the outer wall and terminating short of the similar edge of the flange of the inside wall.

2. A locomotive boiler backhead constituted by an integral casting consisting of an outside wall and a shorter inside wall, the two walls being spaced apart and connected by an imperforate angularly disposed wall portion forming the boundary of a firing opening through the backhead, the end portions of the outside and inside walls being flanged or forwardly turned, a plurality of perforated ribs radiating from the firing opening extending between the outside and inside walls and also connecting their forwardly turned flanges, all of said perforated ribs at their outer portions extending to the marginal edge of the forwardly extending flange of the outside wall and terminating short of the similar edge of the flange of the inside wall, a stoker conduit section integral-

ly formed at its mouth portion with the back-head proper and communicating with the firing opening formed therein, the conduit section extending rearwardly from said back-head and ribs extending between the section and the outer wall, and the upper wall of the conduit section being formed with a ledge extending transversely across the firing opening dividing the same into upper and lower portions, the upper portion being made of suitable size for the manual introduction of fuel therethrough.

In testimony whereof I affix my signature.

E. ARCHER TURNER.
